SWITCH MEANS FOR INDICATING TIME
INTERVALS

Ronald Telford, Newport, Isle of Wight

Application July 22, 1946, Serial No. 685,343
In Great Britain July 23, 1945

5 Claims. (Cl. 200—38)

1

This invention relates to a device for indicating by electrical means the lapse of predetermined time intervals and has for its object the provision of improved and simple means which can be rendered operative at any instant and will then indicate the expiration of a period of time of the selected or predetermined length commencing from the said instant.

According to the invention, a device for indicating by electrical means the lapse of predetermined time intervals comprises a driven element rotated at a constant speed, a pivoted switch lever carrying one electrical contact, disposed adjacent to the said driven element and biased toward another electrical contact serving as a stop for said lever, a pivot carried on the switch lever, a rotatable element eccentrically mounted on the said pivot so that in the normal position of the switch lever it is spaced slightly from the driven element with its maximum eccentricity disposed towards the latter, and latch means normally holding the switch lever away from the contact stop and manually operable to release the pivoted lever at any selected instant to allow the eccentrically mounted element thereon to move into contact with and be driven by the driving element, the consequent rotation of the eccentrically mounted element about its pivot on the lever gradually reducing the gap between the latter and its stop so that the gap is closed at the expiration of a predetermined time interval, thereby completing an electrical warning circuit.

The contact stop referred to is preferably adjustable in relation to the pivoted switch lever so that the duration of the predetermined time interval may be varied as required and a plurality of pivoted switch levers and eccentrically mounted elements may co-operate with a single driven element, the contact stops being either adjustable in common, so that all the switch levers will be operated into engagement with their contact stops in the same period of time (though measured from different starting points if required) or individually adjustable, so that each switch lever will be operated into engagement with its contact stop in a different period of time (again from different starting points if required).

The engagement of the pivoted switch lever with its contact stop is utilized to operate a visual signal or an audible warning, or both, but such engagement may additionally be utilised to effect any desired operation, either directly or indirectly, any desired operation which can be initiated or controlled by the completion of an electric circuit.

In order that the invention may be clearly understood and readily carried into effect, reference will now be made to the accompanying drawings which illustrate one embodiment of

2

the invention by way of example. In the drawings:

Figure 1 is a plan view of the apparatus with a cover removed to expose the mechanism.

Figure 2 is a section taken on the line II—II of Figure 1 but including the cover, the parts of the mechanism being shown in a non-operating position, and

Figure 3 is a view similar to Figure 2, but showing the position of the parts after they have been operated.

The example chosen comprises a plurality of pivoted switch levers and eccentrically mounted elements but, as they are identical in construction and function, only one will be described in detail.

Referring to the drawings, a roller 1 covered with material 2 having a high co-efficient of friction is rotatably mounted between the end walls of a casing 3 near the rear wall 4 thereof and driven at a constant speed by suitable means, for example, a spring-driven clockwork, a synchronous A. C. electric motor or other suitable source of power transmitted at constant speed, this power source being indicated diagrammatically at 5. A pivot spindle 6 is arranged to extend within the casing 3 near the front wall 1 thereof, and parallel with and at a higher level than the axis of the roller 1. Freely pivoted on the spindle 6 is a two-armed switch lever 8 having its shorter arm 9 directed towards the front casing wall 1 and formed with an abutment 10 engageable with the inner end 11 of latch means in the form of a holding key that is pivoted on a spindle 12 adjacent to the front wall 1, and extends at its outer end 13 through a slot 14 in this wall 1. The longer arm 15 of the switch lever 8 extends over and beyond the roller 1 to terminate in an electric contact 16 and carries at a point substantially vertically above the axis of the roller 1 a lateral pivot 17 on which is freely rotatable a circular disc 18 engaged with the pivot 17 by means of an eccentric aperture near its edge. The disc 18 is of a diameter approximately twice that of the roller 1. Mounted to swing about the pivot spindle 6 is an arm or frame 19 carrying another electric contact 20 constituting a stop at the same radial distance from the spindle 6 as the contact 16 on the switch lever 8 and disposed beneath the latter. The position of the contact stop 20 is fixed by means of a clamping nut 21 engaged with a bolt 22 carried on the arm or frame 19 the bolt 22 extending through an arcuate slot 23 in the one end wall 24 of the casing 3, this wall 24 carrying alongside of the arcuate slot suitable graduation marks indicating time intervals.

In the normal inoperative position of the parts as shown by Figure 2 the abutment 10 on the switch lever 8 is engaged by the inner end 11 of

the latching key and thereby held depressed so that the longer lever arm 15 is raised away from the contact stop 23 by an amount permitting the disc 18 to hang freely above the roller 1 with the lower part of its periphery spaced slightly from the latter.

When the outer end 13 of the latching key is depressed to release the switch lever 8 the longer arm 15 thereof with the disc 18 drops until the latter rests on the roller 1. The disc 18 is then driven by the roller 1 about its pivot 17 on the switch lever 8 and, due to its eccentric mounting, the said pivot 17 is gradually lowered until the contact 16 on the lever 15 meets the contact stop 20. The time taken to bring the contacts 16 and 20 together depends on the degree of initial separation thereof.

The contacts 16 and 20 are connected into an electric circuit which includes a signal lamp 25 associated with the appropriate latching key on the front of the casing 3 and which may include also an audible warning device, such as an electric bell or buzzer. Raising of the outer end 13 of the latching key will re-set the pivoted switch lever 8 in its raised position and interrupt the circuit to the signal devices.

One application of the apparatus described is as an indicator for use by the proprietor of a number of articles (such as boats, cars, etc.) which are to be hired out for relatively short periods of time, of the order of half-an-hour, to members of the public. A plurality of pivoted levers 8 is provided with the key for each indicated by a number corresponding to the identification number of an article. The proprietor, therefore, merely depresses the correspondingly numbered latching key as an article is hired and is given warning automatically as the period of time for which that article was hired expires.

Another application is as an indicator for use in kitchens, laboratories and other places where a process requiring a certain fixed period of time for its completion is to be repeated continually. The stops or contacts 20 in such a case would preferably be individually adjustable.

It will be understood that the size or shape of the (or each) eccentrically mounted disc 18 on the (or each) pivoted lever 8 may be varied so as to provide contours of different lengths providing for any desired time lapses before the released switch levers are arrested by their respective contact stops.

I claim:

1. A device for indicating time intervals electrically, comprising, a pair of pivoted contact members both angularly displaceable in substantially the same plane so that their contacts move towards or away from each other, adjustable means maintaining one of said members in a pre-selected angular position, an eccentric connected to the other of said members and a drive member rotatable by a source of power, said drive member being drivably engageable with said eccentric so as to move said second member into contact with said first member.

2. A device for indicating time intervals electrically, comprising, a pair of pivoted contact

members both angularly displaceable in substantially the same plane so that their contacts move towards or away from each other, adjustable means maintaining one of said members in a pre-selected angular position, a driven element rotatable at constant speed and spaced from said other member, an eccentric in the space between said driven element and said other member and connected thereto and drivable by said element and moving said other member toward the first member, and other means holding the other member in a pre-selected angular position disposing said eccentric at a distance from said driven element, said holding means being releasable to permit of engagement between said eccentric and said driven element.

3. The device according to claim 2, and wherein the other member has a second arm and the other means is a releasable holding key engaging said second arm and retaining the eccentric free of the driven element.

4. A device for indicating time intervals electrically, comprising, a pair of pivoted contact members mounted on a common pivot and both angularly displaceable in substantially the same plane so that their contacts move towards or away from each other, adjustable means maintaining one of said members in a pre-selected angular position, a driven element rotatable at constant speed and disposed exteriorly of the pivoted members and between the common pivot and the path of the contacts, and an eccentric carried by the other of said members and engageable with said driven element and rotating the other member toward the first member to cause engagement of the contact members.

5. A device for indicating time intervals electrically, comprising, a pair of contact members mounted on a common pivot for angular displacement in substantially the same plane so that their contacts move toward or away from each other, one of said members being a two-armed lever, an eccentric carried by the larger arm of said member and biased toward the other contact member, adjustable means maintaining the other contact member in a pre-selected angular position, a driven roller rotatable at constant speed and disposed exteriorly of the two members and engageable by the eccentric to drive same, a holding key engageable with the shorter arm to retain the eccentric free of the roller whereby upon operation of the holding key the two-arm member is released for movement toward the other member so as to cause the contacts to engage.
